UNITED STATES PATENT OFFICE.

CHARLES EVANS, OF CHICAGO, ILLINOIS.

PAMPHLET-BINDER.

1,199,062.

Specification of Letters Patent. Patented Sept. 26, 1916.

Application filed October 25, 1915. Serial No. 57,671.

To all whom it may concern:

Be it known that I, CHARLES EVANS, a citizen of the United States, and a resident of Chicago, in the county of Cook and State of Illinois, have invented certain new and useful Improvements in Pamphlet-Binders; and I do hereby declare that the following is a full, clear, and exact description thereof, reference being had to the accompanying drawings, and to the letters of reference marked thereon, which form a part of this specification.

This invention relates to improvements in containers or binders for printed matter and more particularly to an improved binder for temporarily binding pamphlets, catalogues, or printed matter of like nature having covers of paper or like flexible material, or, in short, any form of bound or unbound printed or written matter of the character described.

It is well known to those accustomed to the care and handling of books and familiar with the classification and arrangement of books, periodicals, and like printed matter, and the methods employed in libraries for so doing, that considerable difficulty is experienced in providing for the arrangement and filing of pamphlets and like forms of literature so that this class of printed matter may be properly disposed of according to the usual methods of classification employed in the handling of books, and at the same time protecting and supporting the pamphlets in a manner to prevent them from sagging and bending by their own weight in the absence of proper supporting devices and thereby becoming permanently distorted and otherwise soiled and mutilated. By reason of the nature of pamphlets and like forms of literature, it has been ordinarily found impractical to arrange or classify them with books relating to the same subject or subjects, but, rather, a separate case or file is usually employed in which the pamphlets are stacked or filed in such a manner as to prevent ready access to any particular pamphlet and otherwise complicating the classification of the same for reference purposes.

Among the purposes sought to be accomplished is to provide a temporary binder for pamphlets and like forms of printed matter, designed to overcome the difficulties hereinbefore set forth in the handling and disposition of pamphlets, and to further

facilitate the classification and arrangement of this form of literature, by providing a container designed to receive a pamphlet and provided with means arranged to engage the pamphlet in such a manner as to support the same in upright position within the container. The binder is so constructed as to stand upon edge and hold a pamphlet in an upright position therein. Thus the binder with its inclosed pamphlet can be placed upon the shelves of a bookcase or otherwise handled with the same degree of accessibility, for the purposes of reference and classification, as a book or volume of stiff binding.

The construction of a binder embodying my invention will be understood from the description which follows and in connection with the accompanying drawings, in which—

Figure 1 is a perspective view of the binder in upright position; Fig. 2 is a perspective view looking toward the front or fore-edge of the binder and showing the pamphlet supporting device; and Fig. 3 is a fragmentary detail view showing the manner in which the supporting device is mounted in the binder.

Referring to the drawings, the binder comprises, in general, a hollow container 10 or case of cardboard or like material, open along one side or edge and provided within the interior and adjacent to its open side with a device or attachment designed to act as a support for the pamphlet within the binder, as will hereinafter be pointed out.

The container or case 10 is preferably constructed of stiff cardboard or like material and has the form of a narrow or thin box-like receptacle having side walls 11, 11 and connecting marginal walls on three sides or edges, to wit, a bottom wall 12, a top wall 13 extending along the shorter sides of the container, and a rear wall 14 extending along one of the longer sides, the side opposite said rear wall being open to provide the opening of the container and through which the pamphlet is inserted.

The binder is designed to assume a vertical position when in use, and to rest upon its shorter edge or bottom wall 12 in the same manner as a closed book upon a shelf or other supporting surface, as shown in Fig. 1, with the open side or edge in vertical position.

Although the container may be made of

cardboard, as hereinbefore suggested, it is preferable to make the container in such a manner as to resemble in appearance a closed book, by covering the foundation 5 layers of cardboard with an outer covering of a more expensive grade of paper 15, as shown in Fig. 1, or cloth such as that used in the binding of books. In order to further carry out the resemblance to a closed book, 10 it is desirable to curve the rear or back wall 14 of the binder outwardly to a slight degree, thus providing the appearance of the convexed back, common to the ordinary book. It is preferable to provide upon one 15 of the side walls 11 a space 16 upon which may be printed or written the title of the pamphlet, or other information desired by the reader, this space being either provided directly upon the material of the binder or 20 in the form of a label applied by adhesive to the surface thereof. Similar spaces or labels may also be applied to the back surface of the binder, as at 17, 17 (Fig. 1), for a like purpose.

25 The means for supporting a pamphlet in upright position within the container comprises a rod or wire member 18 extending longitudinally of said container and parallel with and spaced equal distances from the 30 side walls 11, 11. The rod 18 is positioned adjacent to the opening at the fore edge of the container and preferably a short distance inwardly from said opening. The rod 18 is preferably applied to the container 35 during the process of manufacture and in the following manner: The ends of the rod or wire are provided with flattened portions 19, 19, which are extended through the top and bottom walls and bent downwardly at 40 right angles to the rod proper and against the foundation material of the container, as shown in Fig. 3. Upon applying the outer cover 15 of paper or cloth, said ends of the rod 18 are entirely covered thereby and become embedded in the walls of the finished 45 binder.

The function of the rod 18 is, as hereinbefore suggested, to provide a supporting or stiffening member for the pamphlet to be 50 held within the binder, as will be understood from the following: The pamphlet is inserted into the open edge of the binder with its fore edge or unbound edges foremost, the rod 18 being so positioned that it 55 will enter between the leaves of the pamphlet approximately at the center thereof. When the pamphlet has been fully inserted within the binder, its further movement will be limited by the contact of the rod 18 with 60 the bound edges of said pamphlet, said rod or wire being retained between the leaves and against the bound margin. In this manner the rod acts to provide a support, in the nature of a stiffening member, for 65 said rear or bound edge of the pamphlet,

acting to maintain the pamphlet in upright position and preventing the same tilting forward or sagging within the binder and the consequent bending and creasing of the leaves. Furthermore, the rod acts as a stop 70 member, to limit the inward movement of the pamphlet, irrespective of its width, as compared with the depth of the binder, and as a result, the outermost edge of the pamphlet is readily accessible to the grasp of 75 the fingers in removing the pamphlet therefrom.

It is apparent that the binder embodying my invention makes it possible to treat a pamphlet in the same manner as a book, in 80 that it may occupy a position upon a shelf without the use of auxiliary supporting means for holding the pamphlet in an upright and flat position, thus making it possible to conveniently classify and arrange 85 all printed matter relating to the same subject, regardless of whether it is bound in book or pamphlet form, and thus adding greatly to the accessibility of the pamphlet for reference purposes. Furthermore, the 90 pamphlet is protected from dust and injury, and as a result will be maintained in proper condition for subsequent binding. The binder entirely conceals the pamphlet, and at the same time does not itself detract from 95 the slight appearance of a shelf, by reason of its resemblance to a neatly bound volume and its ability to stand upright in the same manner as a bound book.

The details of construction of the binder 100 may be modified without departing from the spirit of the invention, and for that reason I do not wish to be limited except in so far as expressly indicated in the appended claims.

105 I claim as my invention:

1. A binder for pamphlets and the like, comprising a container provided with an opening to receive a pamphlet, and means adjacent to said opening for supporting said pamphlet within said container.

110 2. A binder for pamphlets and the like, comprising a container provided with an opening along one edge thereof, and means adapted to engage a pamphlet inserted in 115 said container to support a margin thereof parallel with said opening.

115 3. A binder for pamphlets and the like, comprising a container adapted to be supported upon edge and provided with an 120 opening arranged to extend vertically of said container, and means mounted in said container and adapted to engage a vertical margin of a pamphlet when inserted in said container to support said pamphlet in up-right position therein.

125 4. A binder for pamphlets and the like, comprising a container adapted to be supported upon edge and provided with an 130 opening at one of its vertical edges adapted

to receive a pamphlet, and a member mounted in said container and extending longitudinally and centrally of the space adjacent to said opening, adapted to engage and support the margin of said pamphlet adjacent to said opening.

5. A binder for pamphlets or the like, comprising a container provided with an opening extending longitudinally and at 10 one edge thereof, and a rod mounted in said container adjacent to and extending parallel with the longitudinal margins of said opening.

6. A binder for pamphlets and the like, 15 comprising a container having side walls, comparatively narrow connecting edge walls, and an opening in one of its longitudi-

nally extending edges, said container being adapted to be supported upon edge with said opening in upright position, and a rod 20 secured at its ends in the top and bottom walls of the container and located a short distance inwardly from said opening and midway between the side walls of said container.

25 In testimony, that I, claim the foregoing as my invention I affix my signature in the presence of two witnesses, this 19th day of October, A. D. 1915.

CHARLES EVANS.
